UNITED STATES PATENT OFFICE.

EMERSON H. STRICKLER, OF NEW YORK, N. Y., ASSIGNOR TO GENERAL CHEMICAL COMPANY, OF NEW YORK, N. Y., A CORPORATION OF NEW YORK.

MANUFACTURE OF MONOALKALI-METAL PHOSPHATE.

1,150,899.

Specification of Letters Patent. Patented Aug. 24, 1915.

No Drawing.

Application filed March 22, 1912. Serial No. 685,584.

To all whom it may concern:

Be it known that I, EMERSON H. STRICKLER, a citizen of the United States, and a resident of the city of New York, State of New York, have invented certain new and useful Improvements in the Manufacture of Monoalkali-Metal Phosphate, of which the following is a specification.

My invention relates to the manufacture 10 of mono-alkali metal phosphates, an example of which is mono-sodium phosphate, which is stated to have, apart from water of crystallization, the formula NaH_2PO_4 .

An object of my invention is to provide a 15 novel process for the production of mono-alkali metal phosphates by which a substantially pure product is capable of being obtained on a commercial scale and at a commercially reasonable cost.

Another object is to provide a cyclic process 20 for the production of mono-alkali metal phosphate in which the residue, after the mono-alkali metal phosphate has been separated out, is introduced into an earlier stage 25 of the complete process, such as that stage at which tri-alkali metal phosphate is made for example in accordance with the process set forth in my Letters Patent No. 744,128, dated November 17, 1903, or in my Letters 30 Patent No. 1,037,837, dated September 3, 1912.

Other objects will be pointed out or will otherwise appear in the following description of my invention, in which, as well as 35 in the appended claims, I use the term "alkali metal phosphate" to include the di- and tri-alkali-metallic salts of phosphoric acid, such as sodium or potassium; "tri-alkali metal phosphate" to include tri- 40 sodium phosphate and tri-potassium phosphate; "di-alkali metal phosphate" to include di-sodium phosphate and di-potassium phosphate; "mono-alkali metal phosphate" to include mono-sodium phosphate and 45 mono-potassium phosphate; and "acid" to include acids free from phosphorus such as sulfuric, nitric, hydrochloric and acetic acids.

Heretofore mono-sodium phosphate has 50 been a laboratory product only. The laboratory methods of producing it are (1) treating phosphoric acid (H_3PO_4) with sodium carbonate until the mixture is neutral, using methyl orange as an indicator; 55 (2) treating tri-sodium phosphate or di-

sodium phosphate with phosphoric acid; or (3) adding alcohol to a solution of di-sodium phosphate in nitric acid.

For commercial and technical purposes, none of the above methods are of utility in 60 obtaining a pure mono-sodium phosphate, principally owing to the presence of impurities, such as iron, alumina, fluorin and organic matter, always contained in commercial 65 grades of phosphoric acid, which impurities are not removable therefrom by commercial and technical operations and which contaminate the mono-sodium phosphate produced therefrom in accordance with the first two of the above laboratory 70 methods and, in the case of the third laboratory method, owing to the prohibitive cost of the alcohol. On the other hand my improved process of making mono-alkali-metal phosphates, which, of course, includes 75 mono-sodium phosphate, is both a commercially available process and one which results in a product commercially free from iron, alumina, and the other impurities above mentioned, a product which is only 80 accompanied by small and, for practical purposes, negligible amounts of other alkali-metal salts, such as, for example, sodium sulfate, sodium chlorid, sodium nitrate or sodium acetate. By proper methods of purification, such as crystallization, the amounts 85 of such accompanying salts can be reduced to any desired degree.

Broadly stated one form of my invention consists in dispensing with the use of phosphoric acid, and in treating an alkali-metal phosphate with an acid free from phosphorus, such as sulfuric acid, hydrochloric acid, nitric acid, which are mineral acids, or 90 acetic acid, which is an organic acid, in such a manner as to produce mono-alkali metal phosphate, and separating this product from the salt of the acid which has been used, without the assistance of alcohol.

Any of the above acids may be added to 100 tri-sodium phosphate, for example, in such amount that mono-sodium phosphate is produced together with the corresponding sodium salt of the added acid.

My invention contemplates a number of 105 modifications in the manner of separating the mono-alkali metal phosphate and the salt of the added acid produced by the above process. The salt of the added acid, in some cases, may be separated out in solid form 110

from the hot liquor, the mono-alkali metal phosphate being contained in the liquor resulting after such separation has been effected, and being separated from said resulting liquor in such manner as will hereinafter be set forth. In other cases the mono-alkali metal phosphate may be separated out in solid form, whether the liquor be hot or cold.

- 10 I have found that if tri-sodium phosphate or di-sodium phosphate or di-potassium phosphate be treated with a sufficient amount of sulfuric acid, or hydrochloric acid, or nitric acid or acetic acid to produce 15 mono-alkali metal phosphate, substantially all of the latter may be separated from the salt of the added acid without the use of any solvent other than water. The salt of the added acid carries with it varying, 20 though small, amounts of phosphate.
- The salt of the added acid carrying with it some alkali metal salt of phosphoric acid, presumably mono-alkali metal phosphate, is, according to my invention, utilized in the 25 production of tri-alkali metal phosphate as for example, by the process described in my Letters Patent No. 744,128, or my Letters Patent No. 1,037,837 hereinbefore mentioned, which tri-alkali metal phosphate 30 may be used in the present process of making mono-alkali metal phosphate. There is thus evolved a cyclic process in which all of the alkali metal products of phosphoric acid are utilized. The mono-alkali metal phosphate 35 moreover, is produced in a substantially pure condition. When the cyclic process is used a complete separation of the mono-alkali metal phosphate and the salt of the added acid is obviously unnecessary 40 because in any case all of the phosphorus contained in the original phosphate is utilized.

In the practice of that example of my 45 cyclic process in which I employ sulfuric acid as the added acid, and which includes the process set forth in the above patent, tri-sodium phosphate is made, by treating "rock-phosphate" *i. e.* calcium phosphate with a solution of niter cake and furnacing 50 the solution thus obtained in the presence of a carbonaceous material, the tri-sodium phosphate thus made is then treated with sulfuric acid in such a manner as to produce mono-sodium phosphate and sodium sulfate, the last mentioned salts are then 55 separated, and the sodium sulfate, carrying with it small amounts of phosphate, is then utilized, as above set forth, in the manufacture of more tri-sodium phosphate. I have 60 described my cyclic process in which sulfuric acid is used and the sulfate of soda produced is employed in the preparation of tri-sodium phosphate. It will be understood, however, that the salts of the other 65 added acids may by suitable modification

be employed with equally successful results. If another acid than sulfuric has been used, the salt of the added acid may obviously be converted into a sulfate by treatment with sulfuric acid so that the processes hereinbefore referred to may be utilized for producing tri-alkali metal phosphate. To the sodium sulfate, produced or recovered in whatever way, the proper amount of crude phosphoric acid should be added so that the proportion between the sulfur and the phosphorus in the resulting mix is that presented in the above referred to patent.

I have further discovered that the separation of the mono-alkali metal phosphate 80 and the salt of the added acid is dependent in large measure upon the particular alkali metal in the phosphate and the particular acid which has been added. In the process of making mono-sodium phosphate in which 85 sulfuric, hydrochloric or nitric acid is used, the resulting sodium sulfate, chlorid or nitrate is first separated out from the hot solution, suitably concentrated; but, when acetic acid is used, the mono-sodium phosphate is preferably first separated out. In separating by crystallization by cooling 90 when sulfuric or nitric acid is used, the phosphate is first separated out.

In making mono-potassium phosphate, 95 potassium sulfate is preferably separated out first, whereas potassium chlorid, nitrate or acetate is separated out last. In separating by crystallization, when acetic acid is used, the phosphate is separated out 100 first; when hydrochloric acid is used, separation by cold crystallization is not so efficacious as hot separation.

The nature of my invention is clearly disclosed by the following specific examples 105 showing various methods of producing mono-alkali metal phosphate from alkali metal phosphate, all of which methods are within the confines of my invention. In these examples, where parts are given they 110 are to be understood as parts by weight. In them I have described my cyclic process only in connection with my preferred acid, which is sulfuric acid.

OPERATING WITH DI-SODIUM PHOSPHATE.

Crystallized di-sodium phosphate contains approximately 12 molecular proportions of water of crystallization; *i. e.* approximately 60% of water. In carrying out 120 my new process with this product I have found it advantageous to take into account the solvent action of the water so introduced into the process and in the case of an acid containing much water such as strong hydrochloric acid, weak sulfuric acid or a weak nitric acid to use practically dehydrated di-sodium phosphate.

Tri-sodium phosphate may be used instead of di-sodium phosphate in all of the 125

processes described for the latter, the processes and results being substantially the same.

5 *A. Using sulfuric acid as the added acid.*

Example I.

(a) Add sulfuric acid, preferably in the form of a 98% acid, to sodium phosphate 10 crystals or solution (crystals preferred) until the mixture is neutral to methyl orange. Concentrate the mixture, if need be, by boiling or evaporation until the solution filtered free of the undissolved material tests 60° Bé. at boiling temperature. Remove the material which separates out in solid form (largely if not wholly sodium sulfate) by filtering or other suitable known method, keeping the solution hot during this 15 removal. Dilute the filtrate with water to approximately 50° Bé. and allow it to cool and crystallize. The product is mono-sodium phosphate. Concentrate the mother liquor by boiling to 50° Bé., allow it to cool and crystallize. This yields a second 20 crop of mono-sodium phosphate. Continue concentration of the mother liquor and crystallization until the product runs too high in sulfate. At this stage it is returned, together with the sodium sulfate, separated 25 during the evaporation, to the sodium phosphate process described in Patent No. 744,128. Instead of boiling down until the solution, free of undissolved material, tests 30 60° Bé. as just described, and separating it all at one time, it may be separated by filtering or otherwise, at two or more different times during the course of the concentration. The operation is continued 35 until the solution tests about 60° Bé. (hot) after the removal of the undissolved material, which is largely if not wholly sodium sulfate.

(b) The process for making mono-sodium 45 phosphate from di-sodium phosphate and sulfuric acid may be modified in the following way: Treat di-sodium phosphate with sulfuric acid as described above, but instead of concentrating the mixture by 50 boiling, add just sufficient water to effect complete solution of any solid salt in the mixture at boiling temperature. The solution should then test about 40° Bé., at boiling 55 temperature. Allow the solution to cool and crystallize. Separate the crystals which are sodium sulfate containing a relatively small proportion of mono-sodium phosphate. These are returned to the sodium phosphate process described in Patent No. 60 744,128. The mother liquor is concentrated to approximately 50° and allowed to cool and crystallize. The crystal product is mono-sodium phosphate. The mother liquor is again concentrated to 50° Bé. and cooled 65 and crystallized. The crystal product is

mono-sodium phosphate. This concentrating and cooling is continued until the mono-sodium phosphate obtained runs too high in sulfate for commercial purposes, when the material still remaining is returned to the 70 sodium phosphate process described in Patent No. 744,128.

75 *B. Using hydrochloric acid as the added acid.*

Example II.

Neutralize di-sodium phosphate with hydrochloric acid using methyl orange as an indicator; concentrate by evaporating to 58° or 60° Bé. and separate the undissolved material by filtration or otherwise, keeping the liquor hot during the operation. The residue separated is principally sodium chloride and may be returned to the sodium phosphate process. Allow the filtrate to cool and crystallize. The crystals thus obtained are mono-sodium phosphate. The mother liquor is treated as were the mother liquors in the preceding examples.

90 *C. Using nitric acid as the added acid.*

Example III.

Neutralize crystallized di-sodium phosphate with nitric acid, using methyl orange 95 as indicator. Concentrate by evaporation to 48° Bé. (test not filtered), allow to cool. Separate the undissolved material which is principally sodium nitrate, by filtering or other known method. Concentrate the filtrate to 50° Bé., cool and crystallize. The crystals are mono-sodium phosphate. The mother liquor may be concentrated and crystallized. The final liquors including the sodium nitrate crystals separated above, are 100 used for making sodium phosphate.

105 *D. Using acetic acid as the added acid.*

Example IV.

110 To 100 parts of anhydrous di-sodium phosphate, add 210 parts of glacial acetic acid containing 99% of acetic acid, $C_2H_4O_2$; digest the mixture for one hour at 212° F.; filter hot; the residue on the filter is crude 115 mono-sodium phosphate and the filtrate is sodium acetate and acetic acid and contains practically no mono-sodium phosphate.

The several grades of mono-sodium phosphate obtained in all the foregoing examples 120 are, if necessary, further purified by suitable crystallization; in the several examples given here there is indicated the probably most advantageous conditions of strength and temperature of solutions for achieving 125 further purification; applying the ordinary experience and rules obtaining in such practice, the mono-sodium phosphate can be freed from accompanying salts of the added acids to any extent needful in commercial 130

operation. In the preceding examples, furthermore, tri-sodium phosphate may be used instead of di-sodium phosphate with correspondingly similar results.

6 OPERATING WITH DI-POTASSIUM PHOSPHATE.

E. Using sulfuric acid as the added acid.
Example V.

- 10 (a) Neutralize a solution of di-potassium phosphate dissolved in water, which solution has a specific gravity of about 1.28 with 98% sulfuric acid using methyl orange as indicator; concentrate by the aid of heat until the supernatant liquor shows 42° Bé.; filter boiling hot; the residue on the filter is practically potassium sulfate. Cool the filtrate, stir while crystallizing and filter; the residue on the filter is a fair grade of crude mono-potassium phosphate; concentrate the 15 filtrate by the aid of heat until it shows 42° Bé.; cool; stir while crystallizing; filter; the residue on the filter is likewise a fair grade of crude mono-potassium phosphate; the 20 filtrate and the residue above containing principally potassium sulfate, may be returned to the potassium phosphate process.
- (b) Instead of stopping the concentration of the neutralized mono-potassium phosphate of the preceding at 42° Bé., it may also be found advantageous to continue the concentration to 46° Bé.; filter hot; the residue on the filter is principally potassium sulfate; bring the filtrate to a boil; add enough hot water to make it test 36° Bé. 25 when hot; cool; stir while crystallizing; filter; the residue on the filter is a fair grade of mono-potassium phosphate; this filtrate and the residue above containing principally potassium sulfate, may be returned to the 30 potassium phosphate process.

F. Using hydrochloric acid as the added acid.

Example VI.

- 45 (a) *Separating crude mono-potassium phosphate from the hot liquor, leaving most of the potassium chlorid in the liquor.*—Neutralize a solution of di-potassium phosphate in water which solution has a specific gravity of about 1.28 with hydrochloric acid (sp. gr. 1.19) using methyl orange as indicator; boil the mixture until a solid begins to separate; continue the boiling until the 50 appearance of the separated solid begins to change; filter boiling hot; the residue on the filter is a fair grade of crude mono-potassium phosphate. The filtrate which tests approximately 38° Bé. may be treated as are 55 the final filtrates in the examples under mono-sodium phosphate.

- (b) *Separating the crude mono-potassium phosphate from the most of the potassium chlorid by crystallization.*—Proceed as 60 under Example VI (a), but stop the boiling

just when solid matter first begins to separate out; now cool, stir while crystallizing and filter; the residue on the filter is in the main mono-potassium phosphate; the filtrate may be treated as is the final filtrate 70 in Example VI (a).

G. Using nitric acid as the added acid.

Example VII.

75 Neutralize a solution of di-potassium phosphate in water, which solution has a specific gravity of about 1.28 with nitric acid (sp. gr. 1.42) boil down until solid matter begins to separate; continue the boiling until the supernatant liquor after testing 44° Bé. has risen to 44.5° Bé.; filter hot; the residue on the filter is principally mono-potassium phosphate. This filtrate may be treated like the final filtrate in Example 80 VI (a).

H. Using acetic acid as the added acid.

Example VIII.

90 (a) *Separating the mono-potassium phosphate by crystallizing it from the potassium acetate.*—To a solution of di-potassium phosphate in water which solution has a specific gravity of about 1.28, add glacial acetic acid, containing about 99% acetic acid ($\text{HC}_2\text{H}_3\text{O}_2$) until a deep red color with methyl red is produced; if any solid separates out heat until it dissolves; cool; stir while crystallizing; filter; the residue on the filter is a very good grade of mono-potassium phosphate; boil the filtrate until a solid just begins to separate, cool; filter; the residue on the filter is a fair grade of mono-potassium phosphate; the filtrate may be treated like the final filtrate of Example 95 VI (a).

100 (b) *Separating the mono-potassium phosphate from the hot liquor leaving most of the potassium acetate in the hot liquor.*—Proceed as under Example VIII (a); but boil the solution obtained after treatment with acetic acid as there described until it tests 27.5° Bé.; filter hot; the residue on the filter is a good grade of mono-potassium phosphate; the filtrate may be treated like 115 the final filtrates under Example VI (a).

I claim:

1. The process of making mono-alkali metal phosphate which consists in treating an alkali metal phosphate with an acid free from phosphorus and separating the mono-alkali metal phosphate and the salt of the added acid produced, in the presence of a non-alcoholic liquid, substantially as and for the purpose described.

2. The process of making mono-alkali metal phosphate which consists in treating an alkali metal phosphate with an acid free from phosphorus and separating the mono-alkali metal phosphate from the salt of the 125

130

added acid produced, by concentrating the solution of the mixture to such a point where substantially all of one of these salts separates out in solid form and separating the 5 solid from the liquid portion.

3. The process of making mono-sodium phosphate which consists in treating sodium phosphate with an acid free from phosphorus and separating the mono-sodium

10 phosphate from the salt of the added acid produced, by concentrating the solution of the mixture to such a point where substantially all of the sodium salt of the added acid separates out in solid form and separating the solid from the liquid portion.

15 4. The process of making mono-sodium phosphate which consists in treating sodium phosphate with sulfuric acid and separating the mono-sodium phosphate from the sodium sulfate produced, by concentrating the solution of the mixture to such a point where substantially all of the sodium sulfate separates out in solid form and separating the solid from the liquid portion.

20 5. Process of separating mono-alkali metal phosphate from an alkali metal salt of an acid free from phosphorus which comprises concentrating the solution of the mixture to such a point where substantially 25 all of one of these salts separates out in solid form and separating the solid from the liquid portion.

30 6. Process of separating mono-sodium phosphate from the sodium salt of an acid free from phosphorus which comprises concentrating the solution of the mixture to such a point where substantially all of the sodium salt of the added acid separates out in solid form and separating the solid from 35 the liquid portion.

40 7. Process of separating mono-sodium phosphate from sodium sulfate which comprises concentrating the solution of the mixture to such a point where substantially all 45 of the sodium sulfate separates out in solid form and separating the solid from the liquid portion.

45 8. The cyclic process of making mono-alkali metal phosphate which consists in 50 treating an alkali metal phosphate with an

acid free from phosphorus, separating the mono-alkali metal phosphate and the salt of the acid produced, converting the separated salt of the added acid by a suitable process into alkali metal phosphate, and 55 utilizing the last mentioned alkali phosphate in a repetition of the above operations, substantially as and for the purpose described.

9. The cyclic process of making mono-alkali metal phosphate which consists in first making alkali metal phosphate by treating a phosphate containing substance with an acid alkali metal sulfate and furnacing the result in the presence of carbonaceous material, then treating the alkali metal phosphate, thus produced, with an acid free from phosphorus to produce mono-alkali metal phosphate and an alkali metal salt of the added acid, then separating the last-mentioned salts, then converting the separated alkali salt of the added acid into acid alkali sulfate and finally utilizing the last mentioned acid alkali sulfate in a repetition of the above operations, substantially 75 as and for the purpose described.

10. The cyclic process of making mono-alkali metal phosphate which consists in first making tri-alkali metal phosphate by treating a phosphate containing substance 80 with an acid alkali metal sulfate and furnacing the result in the presence of carbonaceous material, then treating the tri-alkali metal phosphate, thus produced, with sulfuric acid to produce mono-alkali metal 85 phosphate and an alkali metal sulfate, then separating the last mentioned salts, then converting the separated alkali metal sulfate into acid alkali metal sulfate and finally utilizing the last mentioned acid alkali metal 90 sulfate in a repetition of the above operations, substantially as and for the purpose described.

In testimony whereof I have hereunto set my hand in the presence of two subscribing 95 witnesses.
